US00D838277S

(12) **United States Design Patent** (10) **Patent No.:** **US D838,277 S**
Asai (45) **Date of Patent:** **** Jan. 15, 2019**

(54) **DISPLAY PANEL OR SCREEN WITH A GRAPHICAL USER INTERFACE**

(71) Applicant: **Sony Corporation**, Tokyo (JP)

(72) Inventor: **Satoshi Asai**, Saitama (JP)

(73) Assignee: **SONY CORPORATION**, Tokyo (JP)

(**) Term: **14 Years**

(21) Appl. No.: **29/463,646**

(22) Filed: **Jan. 28, 2014**

(57) **CLAIM**

The ornamental design for a display panel or screen with a graphical user interface, as shown and described.

DESCRIPTION

FIGURE is a front elevational view of a display panel or screen with a graphical user interface showing my new design.

The broken line showing of the display panel or screen with a graphical user interface form no part of the claimed design.

1 Claim, 1 Drawing Sheet
